UNITED STATES PATENT OFFICE

CADWELL A. WILLIAMS, OF WILMINGTON, NORTH CAROLINA

CONNECTING DEVICE FOR RAILROAD-SIGNAL CIRCUITS

Application filed February 3, 1926. Serial No. 85,628.

This invention relates to improved connecting devices for railway signal circuits and is concerned particularly with the improvements whereby underground cables may be led into concrete bootlegs and connections readily made between the wires therein and the rails through means which of themselves serve important mechanical purposes in centering the end of the cable and provide the electrical connection desired. In combination with such improved means it is proposed to associate devices for protecting the wiring against the elements while affording maximum accessibility for completing or interrupting the circuits. More particularly, the improvements are designed to enlarge the usefulness of so-called parkway cables which are adapted to be laid directly in the earth and need only convenient facilities for electrical connections to the rails at intervals for widespread adoption. By the present improvements this type of cable may be led into bootlegs either through the bottom or side walls and held centered in convenient position for connection of the wires to terminals, these terminals affording convenient and accessible binding posts for the rail bond connections. In accordance with the improvements it is proposed to employ a terminal sleeve of high conductivity and mechanical strength which itself receives the end of the cable and holds it centered and in addition carries the binding posts to which the feed wires and the rail wires are attached, the terminal sleeves themselves acting as conductors. The support for the sleeve is the concrete bootleg or the like shouldered and recessed similarly to the sleeve and a similar sleeve of insulating compound is interposed between the bootleg and the terminal. An iron cap may be bolted directly over the terminal connections to protect them from the weather and afford outlet openings for the bond wires. Reference is now to be had to the accompanying drawings for a detailed description of one suitable embodiment of the invention, wherein:

Figure 1 is a view in section through all of the improved devices and through a rail, the electrical connections being conventionally indicated.

Figure 2 is a horizontal view in section through the covering cap and taken on the plane indicated by the line 2—2 of Figure 1 and looking in the direction of the arrows.

Figure 3 is a view in elevation of a binding post for attachment to the terminal sleeve.

It will be understood as the description proceeds that the invention is not to be limited to the form or composition of some of the elements illustrated since they may be of any conventional character known to the art and adapted to serve their intended functions. However, for clearness and emphasis the description will be addressed to an assembly in which there is provided a parkway cable *a*, a concrete bootleg *b* and a tapered terminal *c* for the wire *c'* leading to the rail *d*. In the use of parkway cable it is desirable to provide for convenient anchorage therefor and electrical connections therebetween. This cable may be led into a concrete bootleg *b* either through the bottom or side walls thereof. In accordance with the invention it is proposed to recess the concrete bootleg *b* on its upper face as at *b'* this recess being shouldered and merging into the central opening *b*² through the bootleg into which the cable extends. The shoulder *b*³ in the recess *b'* is adapted to support, in a manner which will now be described, the improved terminal devices. A metal sleeve *d* constitutes the terminal and is formed with a peripheral flange *d'* at its upper end to serve the two-fold purpose of receiving suitable binding screws *e* and affording a support for the terminal by coaction with the shoulder *b*³ in the bootleg. This terminal sleeve *d* may be of any desired metal of suitable conductivity and durability to meet the conditions of use brass, for instance, having been found satisfactory. The bore of the sleeve *d* is preferably of such diameter with reference to the exterior diameter of the cable *a* as to receive the cable somewhat snugly and hold it centered and anchored against dislodgment. Further, the sleeve is of sufficient length to adapt it to this centering function so that it will overlie a comparatively substantial length of cable. Interposed between the terminal sleeve *d* and the concrete bootleg is a similar sleeve *d* of insulating compound

which embraces the terminal sleeve *d* snugly and in addition extends around the edge of the flange *d'*. This insulating compound rests directly in engagement with the shouldered concrete bootleg and protects the terminal against electrical leakages, short circuits and the like in a manner which will be apparent from the relationship of parts illustrated in Figure 1. In the preferred form the flange *d'* of the terminal sleeve *d* has a plurality of openings *d*² therein as many as four in number being shown in Figure 2. The binding screw *e* as illustrated in Figure 3 may be threaded in two or more of these openings *d*² and locked in place by a nut *e*, a lock nut *e*² being also provided for clamping when the wires are finally secured to the binding screws. The feed wire *a'* of the cable *a* is led to one of the binding posts *e* while the bond wires *c'* are connected to others of the binding posts *e*, the metal of the terminal sleeve itself acting as a conductor between the posts to complete the circuit. Over the junction members described may be fastened a cap *f* to keep out the weather this cap having a channel *f'* at one side to accommodate the wires *c'* and itself being readily detachable to afford ready access to the parts for connection or interruption of the circuits.

The elements illustrated are such as to be most conducive to ready assembly, electrical connections, inspection and repairs. The cables *a* when led up through the bootleg *b* find a convenient centering member in the terminal sleeve *d*. This cable is held against accidental dislodgment in a most effective manner by this terminal sleeve. Insulation protects the terminal sleeve in its seat on the concrete bootleg. Electrical connections between the various parts are easily made through the binding post carried with the terminal sleeve.

As pointed out hereinbefore changes in the particular nature of the elements and in the materials thereof may be made without departing from the spirit of the invention.

What I claim is:

1. In combination, a bootleg having a shouldered recess at its upper end, a terminal sleeve extending down into the bootleg to receive and center a cable, a flange on the sleeve adapted to be supported on said shouldered recess, said sleeve and flange being insulated from the ground, and means on the flange of the sleeve for connection with outside wires.

2. In combination, a bootleg having a shouldered recess at its upper end, a flanged terminal sleeve adapted to be supported on said shouldered recess and extend down into the bootleg to receive and center the cable, and insulating composition interposed between the bootleg and the sleeve.

3. In combination, a bootleg having a shouldered recess at its upper end, a flanged

terminal sleeve adapted to be supported on said shouldered recess and to extend down into the bootleg to receive and center a cable, insulating composition interposed between the bootleg and the sleeve, and means electrically connected with the said terminal to complete electrical connection from the cable.

4. In combination, a bootleg having a shouldered recess at its upper end, a flanged terminal sleeve adapted to be supported on said shouldered recess and to extend down into the bootleg to receive and center a cable, insulating composition interposed between the bootleg and the sleeve, means electrically connected with the said terminal to complete electrical connection from the cable, and means electrically connected with the said terminal to provide for electrical connection with an outside electrical conductor.

5. In combination, a bootleg having a shouldered recess at its upper end, a flanged terminal sleeve adapted to be supported on said shouldered recess and to extend down into the bootleg to receive and center a cable, insulating composition interposed between the bootleg and the sleeve, means electrically connected with the said terminal to complete electrical connection from the cable, means electrically connected with the said terminal to provide for electrical connection with an outside electrical conductor, and a removable cap to cover the top of the bootleg.

6. In combination, a bootleg having a shouldered recess at its upper end, a terminal sleeve having a flange adapted to be supported on said shouldered recess and to extend down into the bootleg to receive and center the cable, said sleeve being insulated from the ground binding posts on the flange of the sleeve for connection with outside wires, and a cap to cover the top of the bootleg.

This specification signed this 15th day of June, A. D. 1925.
